UNITED STATES PATENT OFFICE.

CHARLES W. NEWTON, OF BOSTON, MASSACHUSETTS, ASSIGNOR TO UNITED SHOE MACHINERY CORPORATION, OF PATERSON, NEW JERSEY, A CORPORATION OF NEW JERSEY.

VAMP-PERFORATING MACHINE.

Application filed September 23, 1920. Serial No. 412,126.

To all whom it may concern:

Be it known that I, CHARLES W. NEWTON, a citizen of the United States, residing at Boston, in the county of Suffolk and State 5 of Massachusetts, have invented certain Improvements in Vamp-Perforating Machines, of which the following description, in connection with the accompanying drawings, is a specification, like reference characters on the drawings indicating like parts in the several figures.

This invention relates to machines for operating on sheet material and is herein shown as embodied in a machine for perforating vamps.

In the manufacture of boots and shoes, it is usual to ornament certain parts of the upper by punching designs therein by means of a gang punch. When it is desired so to 20 use a pattern punch to ornament some shoe parts, as the toe portion of a vamp on a wing tip, difficulty is encountered in presenting the work to the machine in the proper manner for the reason that the toe portions 25 of vamps are not symmetrical, and their outlines differ according as they are rights or lefts and according to their sizes. Moreover, the longitudinal position of the design to be punched varies, its distance from the 30 center of the throat of the vamp varying in different styles of shoes. Again, the pattern punches vary, the perforating tubes being located at different distances from the edges of the dies. Furthermore, when a 35 vamp is to be provided with a line of perforations, or with an ornamental medallion, it is often desirable to "angle" the design, that is, to place that portion of the design on the outer side of the shoe slightly 40 rearward of that portion on the inner side. On right and left shoes this displacement of the design is equal and in opposite directions.

An object of the invention, therefore, is 45 to provide a satisfactory mechanism for positioning vamps to be perforated and so constructed that it may be effectively utilized to position vamps or wing tips of different styles with respect to various perforating or other ornamenting mechanism under the varying conditions existing in different factories and of such a nature that it will permit the operator to work at a maximum speed with a minimum possibility of error.

With this object in view, there is provided 55 in the illustrated machines, in combination, a cutting block, a perforating die for ornamenting a vamp and a vamp support connected to the die and movable with respect to the cutting block to carry the vamp from 60 a vamp positioning to a vamp perforating position. Features of the invention include also, means for adjusting the vamp angularly to position the ornamentation at an angle to the center line of the vamp and 65 means for taking care of variations in the style of vamp or the die.

Although the term "vamp" has been used repeatedly throughout the specification and claims, that term has been used merely for 70 convenience and is intended to cover, where the context and prior art permit, not only vamps, but wing tips or other parts of shoes to be ornamented. Although the invention has been illustrated as being in the nature 75 of an attachment for existing machines, it should be understood that it is in no way limited in that respect.

Referring to the drawings:

Figure 1 is a perspective view of a perforating machine in combination with one form of vamp gage;

Fig. 2 is a perspective view of the under side of the vamp carrier;

Fig. 3 is a perspective view, partly in section of the vamp carrier;

Fig. 4 is a perspective view partly in section of a detail;

Fig. 5 is a vertical, central section of the perforating machine showing the vamp carrier, die and vamp in a punching position;

Fig. 6 is a top plan view of the die, gage and vamp carrier;

Fig. 7 is a perspective view of a detail;

Fig. 8 is a perspective view of the detachable connection between the die and vamp carrier;

Fig. 9 is a perspective view of a modified form of perforating machine together with a modified form of gage;

Fig. 10 is a vertical, central section thereof;

Fig. 11 is a perspective view partly in section of a detail;

Fig. 12 is a top plan view of the vamp gage of Fig. 9 and its support; and

Fig. 13 is a perspective view of the gage support, the parts being separated.

In the embodiment shown in Figs. 1 to 8, the punch and vamp gage are secured together for joint sliding movement toward and from the die block. At 8 is indicated the usual cutting block or bed over which is fed the paper backing strip 10 and, below these, is the die holder 12 having projecting ledges 14, at the sides to engage and slide along the ways 16 on the frame of the machine. On the die holder 12 is a two-part punch plate 18 in which are secured hollow punches 20 which are arranged in the desired design of ornamentation. There is mounted on the punch plate 18 a 15 perforated stripper plate 22 carrying turn buttons 24 for holding the work. In place of the usual edge gage which projects above the stripper plate I have provided a filler plate 26 which is yieldingly mounted and 20 comes flush with the top face of the stripper plate. The die or punch is inserted beneath the die block, with its "toe" end towards the rear, this being the reverse of the usual arrangement.

25 In the form of the invention shown particularly in Fig. 1, the vamp is first placed in the desired position on a carrier while it is free and clear of the cutting block. The vamp carrier and the die are secured 30 together, and, when the vamp is positioned, all these members are moved rearwardly to a punching position. For this purpose, there is bolted to the frame of the machine, a pair of inclined guide bars 30, on which 35 slides a skeleton slide block 32 which, with the attached parts, constitutes the vamp carrier. Suitable guide lugs 34 projecting downwardly from the slide block 32 direct its movement toward the punch. As the 40 style of die or punch is frequently changed, it is desirable to have the die detachably connected to the vamp carrier and gage. As shown in Fig. 8, this detachable connection consists of headed screws 36 projecting from the die holder 12 and adapted to enter apertures 40 formed in lugs 38 on the rear of the slide block 32. To lock 45 these parts in position, there are provided lock plates 44 slidably mounted in guides 42 on the block and having finger pieces 46 by which they may be moved. Each lock plate 44 is provided with an aperture of the size of the aperture 40 and also with a narrow slot, so that upon sliding the plate, 50 it will engage behind the head of the screw 36 to secure the die and vamp carrier together. A stop 48 may be used to indicate when the apertures are in registration.

55 In the various styles of dies the punches are frequently fixed at different distances from the edges of the dies. It is therefore desirable to have an initial adjustment of the die with reference to the vamp support and gage. For this reason the slide 60 block 32 is provided with a cut out portion 50, and, moving in ways 54 of the slide block, and in the cut out portion, is a slide member 52 carrying the vamp support and gage. The slide member has a vertical flange 56 at its front end (Fig. 4), this 70 flange having slots for guided movement along the ways 54. Attached to an intermediate portion of the slide member 52 by means of a screw 60, (see Figs. 3 and 5) is a bar 58 forked at its ends and having pointers or indices 62 for co-operation with scales 64 on the face plates 66 of the block. These scales 64 are graduated in accordance with a characteristic of the die and are marked by numbers which may be placed 75 along the scales, these numbers corresponding to similar numbers which may be stamped on the different dies.

80 For securing the slide member 52 to an operating means after the initial adjustment has been made, there is provided a pivot screw 68, which is threaded upwardly into the member 52, and a bushing, consisting of a reduced portion 74 which slides in a slot 70 of the block 32 and of an enlarged 85 shouldered portion 76, to which is clamped a link 80. This link is slotted, as indicated at 78, and a clamp nut 82, threaded on the bushing, secures the link to the slide member 52. The bushing is loosely swiveled on 90 the pivot screw 68 so that there is provision for swinging movement of the link. The link is connected at its other end to an operating lever through the following grade 95 adjusting connections. At the end of the link is a pivot 84 secured to an adjustable block 86 mounted to slide in a groove of the arm 88 pivoted at 90 to the slide block. The block 86 has an indicator or pointer 100 94 for co-operation with a scale on the arm 88 and a clamp screw 92 holds the block in adjusted position. This last adjustment is to provide for the varying of the "grade" as it is called and it is not necessarily used 105 since the size variations are quite generally standardized. If a different system of size measurement is used, however, the placing of the pivot 84 nearer to or farther from the pivot 90 will alter the throw of the link and the vamp gage to which it is connected. 110 After the preliminary adjustments have been made, the vamps are progressively positioned and punched throughout the series of sizes, as described hereinafter, the lever 98 being moved over a sector-shape 115 member having a scale 100 with size indications thereon.

120 Since to permit the normal functioning of the stripper plate, the work and its supporting means must "give" a little, the gage plate 116 which carries the vamp positioning means, is mounted to have pivotal movement about the pivot screws 108 (Fig. 2). These screws 108 are carried by a member 112 having interposed between it and the 125 130

slide member 52 a spring 110. The gage plate 116 is mounted for sliding movement in ways 114 carried by the member 112 and has, at its front end, a lug 118 for locating the throat of the vamp and, at its other end, a slot, on the sides of which are graduated scales 120. A suitable clamping block 124, having pointers 126 for co-operation with these scales, is slidably mounted in the slot and has a clamping screw 122 threaded in the member 112 to hold the gage plate 116 in adjusted position. This adjustment is provided to take care of the differences in the styles of vamps, as for instance, where there is a variation in the distance of the perforations from the throat of the vamp.

In punching the vamp, it is often desirable to angle the perforations with respect to the vamp center line. For this purpose, the gage plate 116 has a series of arc shaped guide slots or ways 130 (see Fig. 7), in which is mounted a guide plate 132 having arcuate guide projections 134. The slots and projections are curved about a center at the lug 118 so that the vamp will be moved angularly about its throat as a center. Guide washers 136 may be secured to the projections to prevent the escape of the guide plate. To indicate the extent of the angular movement, there is attached to the guide plate, a pointer 138 for co-operation with a scale 140 on the gage plate. To effect this angular adjustment, an extension 142 of the guide plate may be swung to the right or left by a clamp screw 144 passing through an arc shaped slot 146 in the gage plate. For supporting the vamp as it turns through this angle there is attached to the guide plate at 152 by means of screws a vamp supporting plate 150. This plate 150 may have parallel numbered lines to aid in positioning a so-called circular or short vamp if such work is to be punched. Secured to the guide plate 132 is a rear set of V-arms or gage members 154 mounted to swing about the pivot 156. These arms are constrained to move equally with reference to the vamp center line by means of links 158 pivoted at one end to the arms and being pivoted at their opposite ends to a pin 160 sliding in a slot 162 on the guide plate. Attached by means of the pivot 166 to the vamp supporting plate 150 is a forward set of V-arms or gage members 164. These arms are connected pivotally to links 168 which, in turn, are secured to a pin 170 sliding in a slot 172 in the plate 150.

To render easy the movement of the die and vamp carrier from the position shown in Fig. 5 to that shown in Fig. 1 there is secured to these members a counter weight device. This consists of a bracket 176 secured to the block 32 and a cable 178 passing around a fixed pulley 180 and a mov-

able pulley 182 and secured to the frame of the machine. The movable pulley 182 is carried on a treadle 184 having a weight 186 which approximately balances the weight of the vamp carrier and die.

In operation, the desired die is first selected and secured to the carrier by the connection shown in Fig. 8. The parts are then placed in the position shown in Figs. 1 and 6 and the vamp positioned around the gage arms with its throat against the lug 118. The initial adjustment to compensate for the style of die is made by loosening the nut 82 and moving the slide member 52 until the indicator 62 comes opposite the desired number on the scale 64. This number is obtained either from the die or from a die schedule with which the operator is furnished. The nut 82 is then tightened to clamp the slide member 52 to its operating means. The initial adjustment to compensate for the style of vamp is made by loosening the clamp screw 122 and moving the gage plate 116 in the ways 114 until the pointer on the block 124 is opposite the desired number on the scale 120. This number is obtained from the work ticket and determines the distance of the perforations from the throat of the vamp. The clamp screw 122 is then tightened to secure the gage plate to the member 112 and slide member 52.

To center the vamp, the gage arms 154 and 164 are spread apart until both sets meet the side edges of the vamp throat and this movement may slide the vamp sideways somewhat on the supporting plate 150 until the vamp is centered. If it is desired to "angle" the vamp, the screw 144 is loosened and the guide plate 132, supporting plate 150 and gage arms are swung to the right or left on the gage plate 116 until the desired position is indicated by the scale 140 and pointer 138. The screw 144 is then tightened and the lever 98 moved along the size scale 100 to the number corresponding to the size of the vamp. The connected die and vamp carrier are then slid down the guide bars 30 as far as they will go whereupon the cutting block 8 is caused to descend to perforate the work. When the die and carrier are again moved forwardly, the vamp of the next size is selected and positioned, the only correction thereafter necessary for the progressive punching of the vamps being the swinging of the lever 98 along its scale in accordance with the size.

In Figs. 9 to 13 inclusive, I have shown another form of perforating machine and a modified form of vamp gage. The perforating die is not mounted to slide as in the other form. In these figures I have indicated parts corresponding to those in the other form of my invention by means of reference numerals having an additional 200. 130

In this machine there is provided a cutting block 208 for co-operation with a punch plate 218 and a stripper plate 222. Attached to a bracket 230 on the frame is a block 232 secured in place by means of suitable clamp screws 234 and 236. Mounted adjustably in ways 254 in the block 232 is a slide member 252, the position of this slide member being indicated by a scale 264. On 10 the block 232. This scale co-operates with an index 262 on the slide member and the adjustment is to provide for the style of die. After this adjustment has been effected the slide member 252 is connected to 15 an operating means in a manner similar to that described in the other form. Secured to the slide member 252 is a pivot screw 268 movable in a slot 270 on the block 232. Around this pivot is swiveled a bushing comprising a portion 274 reduced to slide in the slot 270 and an enlarged shouldered portion 276 for clamping engagement with a slot 278 in a link 280. The link is pivotally connected at 284 with an operating lever 298 which, in turn, is pivoted to the block 232 at 290. A scale 300, graduated in vamp sizes, is arranged for co-operation with the lever 298.

Mounted in ways 314 in the slide member 252 is a gage plate 316 from which extends a dove-tailed slide tongue 317. The sliding movement is provided to give an adjustment in accordance with the style of vamp and the adjustment is indicated preferably by 35 means of an index 326 on the tongue 317 and a scale 320 on the sides of the slide member 252. The scale and index may be reversed, if desired and the parts may be secured together by a clamp screw 322 threaded in the 40 gage plate 316 and abutting the member 252.

For "angling" the vamp to the right and left to place the ornamentation at an angle to the center line, the following mechanism is utilized: The gage plate 316 has arcuate 45 guide slots 330 in which are mounted arcuate guide plates 332 secured by the screws 352 to a vamp supporting plate 350. The amount of angular movement is indicated by means of a pointer 338 on the supporting 50 plate co-operating with a scale 340 on the gage plate 316. The supporting plate 350 may be clamped in adjusted position by means of a clamp screw 344 threaded in the gage plate 316 and passing through an arc-shaped slot 346 in the supporting plate.

For engaging the side edges of the throat of the vamp to center the latter on the supporting plate, there are provided front and rear sets of gage arms. The rear set comprises arms 354 pivoted at 356 and constrained to move together by means of the links 358. These links are pivoted at their meeting ends to a slide block 362 mounted to move in a slot in the supporting plate. 60 A similar set of front gage arms 364 are

pivoted at 366 and connected together by means of links 368 pivoted at 370 to a block 372 sliding in a slot in the supporting plate.

To position the throat of the vamp, there is secured to the plate 350 a bracket 374 to 70 which is pivoted a member 376, this member being held normally in a slightly raised position above the stripper 222 by means of a spring 378. This spring allows the member to yield under punching pressure. 75

In the operation of this modified form, the preliminary adjustments to compensate for the different styles of dies and for the different styles of vamps are made in a manner similar to that described with reference to Figs. 1 to 8. The vamp is centered on its supporting plate 350 by means of the throat engaging member and the gage arms. If the vamp is to be "angled," the clamp screw is loosened and the supporting plate swung to the right or left to the desired extent indicated by the scale 340. The toe portion of the vamp then projects rearwardly the proper distance between the die and cutting block to receive the perforations. The progressive punching of the vamps is then continued throughout the series of sizes, by successive adjustments of the lever 298 over the size scale 300.

Having thus described my invention, 95 what I claim as new and desire to secure by Letters Patent of the United States is:—

1. The combination with a perforating machine having a cutting block, of vamp positioning means mounted to slide with reference to the cutting block, a perforating die, and means to adjust the positioning means angularly to position the perforations at an angle with respect to the center line of the vamp. 100

2. The combination with a vamp perforating machine having a cutting block and a perforating die for ornamenting the vamp, of vamp positioning means, and means to adjust the positioning means angularly to place the perforations at an angle to the center line of the vamp. 110

3. The combination with a perforating machine having a cutting block, of a gage plate mounted to slide with reference to the cutting block, vamp positioning means movably mounted on the gage plate, a perforating die, and means to adjust the positioning means angularly to place the perforations at an angle to the center line of the vamp. 115

4. The combination with a perforating machine having a cutting block, of a perforating die, a gage plate mounted to slide with reference to the cutting block, a guide plate mounted to move angularly with respect to the gage plate, vamp gage arms pivotally carried by the guide plate, and means to adjust the guide plate angularly to place the perforations at an angle to the center line of the vamp. 125

5. The combination with a perforating machine having a cutting block, of a perforating die, a gage plate mounted to slide with reference to the cutting block and having a vamp throat engaging member, a guide plate mounted to move angularly about the throat engaging member, vamp gage arms carried by the guide plate, and means to adjust the guide plate and gage 10 arms angularly to place the perforations at an angle to the center line of the vamp.

6. In a perforating machine, in combination, a cutting block, vamp positioning means, a gang punch for ornamenting the 15 vamp, and means for swinging the vamp positioning means with respect to the gang punch to position the perforations at an angle to the center line of the vamp.

7. In a vamp perforating machine having a cutting block and a perforating die, a supporting plate for supporting the vamp, and means to adjust the supporting plate angularly to position the perforations at an angle to the center line of the vamp.

25 8. In a vamp perforating machine having a cutting block and a perforating die, a movable plate for supporting the vamp, gage arms mounted to move with the supporting plate, and means to adjust the supporting plate angularly to place the perforations at an angle with respect to the center line of the vamp.

35 9. In a vamp perforating machine having a cutting and a perforating die, a movable plate for supporting the vamp, pairs of gage arms pivoted with respect to the supporting plate, and means to adjust the supporting plate and gage arms angularly to set the perforations at an angle to the 40 center line of the vamp.

10. In a vamp perforating machine, in combination, a cutting block, a gang punch for ornamenting the vamp, a gage plate having a member to engage the throat of 45 the vamp, and vamp gage arms mounted to move angularly about the throat engaging member.

11. In a vamp perforating machine, in combination, a cutting block, a gang punch for ornamenting the vamp, a gage plate having a member to engage the throat of the vamp, a vamp supporting plate mounted to move angularly about the throat engaging member, and gage arms mounted 55 to move with the supporting plate.

12. In a vamp perforating machine, in combination, a cutting block, a gang punch for ornamenting the vamp, a gage plate having arcuate guideways, a guide plate 60 mounted to move in the guideways angularly about the throat of the vamp, and gage arms mounted to swing angularly with the guide plate.

13. The combination with a perforating machine having a movable cutting block, a

guide, vamp positioning means mounted to slide on the guide, a perforating die, and means to adjust relatively the positioning means and the perforating die to set the perforations at an angle to the center line 70 of the vamp.

14. The combination with a perforating machine having a movable cutting block, of a fixed guide, vamp positioning means mounted to slide on the guide, a perforating die mounted to move with the positioning means, and means to adjust the positioning means angularly to place the perforations at an angle with respect to the center line of the vamp. 75

15. The combination with a perforating machine having a movable cutting block, of a fixed guide, a slide block mounted to slide on the guide, a perforating die secured to the slide block, and vamp positioning means constructed and arranged to swing angularly with respect to the perforating die. 80

16. The combination with a perforating machine having a movable cutting block, of a fixed guide, a slide block mounted to slide on the guide, a perforating die secured to the slide block, a gage plate carried by the slide block, vamp positioning means mounted on the gage plate and constructed and arranged to swing angularly with respect to the perforating die. 85

17. The combination with a perforating machine having a movable cutting block, of a fixed guide, a slide block mounted to slide on the guide, a perforating die secured to the slide block, a slide member mounted to move on the slide block, a gage plate initially adjustable on the slide member in accordance with the style of vamp, and vamp positioning means mounted on the gage plate and constructed and arranged to swing angularly with respect to the perforating die. 100

18. The combination with a perforating machine having a movable cutting block, of a fixed guide, a slide block mounted to slide on the guide, a perforating die secured to the slide block, a slide member initially adjustable on the slide block in accordance with a characteristic of the die, means to adjust the slide member thereafter on the block in accordance with the size of vamp, and vamp positioning means constructed and arranged to swing angularly with respect to the perforating die. 115

19. The combination with a perforating machine having a movable cutting block, of a fixed guide, a slide block mounted to slide on the guide, a perforating die secured to the slide block, a slide member initially adjustable on the slide block in accordance with a characteristic of the die, means to adjust the slide member thereafter on the block in accordance with the size of vamp, a gage 125

plate initially adjustable on the slide member in accordance with the style of vamp, and vamp positioning means mounted on the gage plate for angular movement.

5 20. The combination with a perforating machine having a movable cutting block, of a fixed guide, a slide block mounted to slide on the guide, a perforating die secured to the slide block, a gage plate carried by 10 the slide block, a guide plate mounted to swing relatively to the gage plate, and a vamp supporting plate and gage arms mounted to swing with the guide plate to move the vamp angularly for perforating.

15 21. The combination with a perforating machine having a movable cutting block, of a fixed guide, a slide block mounted to slide on the guide, a perforating die secured to the slide block, a gage plate carried by the 20 slide block and having arcuate slots, a guide plate having arcuate projections mounted in the slots, a vamp supporting plate secured to the guide plate, gage arms mounted on the guide plate and vamp supporting plate, 25 and means to adjust the guide plate to the right or left to set the perforations at an angle with respect to the center line of the vamp.

30 22. The combination with a perforating machine having a movable cutting block and a fixed guide, of a combined vamp carrier and perforating die slidable on the guide from vamp setting to vamp perforating position, and means to adjust the vamp angularly on the carrier.

35 23. The combination with a perforating machine having a movable cutting block, and a fixed guide, a vamp carrier mounted to slide on the guide, means to adjust the vamp angularly on the carrier, and a perforating die secured to the carrier to slide with the latter from a vamp positioning to a vamp perforating position.

40 24. The combination with a perforating machine having a cutting block and an inclined guide, a vamp carrier mounted to slide on the inclined guide, a perforating die secured to the carrier, and a counterweight to enable the sliding parts to be moved easily 45 from vamp perforating to vamp setting position.

45 25. The combination with a perforating machine having a cutting block, a perforating die, a vamp support constructed and arranged to swing on a pivot under perforating pressure, a spring to restore the vamp support to initial position when the pressure is released, and means to adjust the vamp angularly on its support.

50 26. The combination with a perforating machine having a cutting block, of a slide block mounted to slide with reference to the cutting block, a gage plate having pivotal connection with the slide block, a spring acting to lift the gage plate and adapted to

yield under punching pressure, means to adjust the vamp angularly with respect to the gage plate, and a perforating die secured to the slide block to move with the latter.

55 27. The combination with a perforating machine having a cutting block and a perforating die, a block having ways, a slide member adjustable in the ways, means to adjust the slide member in the ways in accordance with the size of vamp, and a vamp supporting plate mounted to move with the adjustable slide member and having provision for angular movement.

60 28. The combination with a perforating machine having a cutting block and a perforating die, a block having ways, a slide member adjustable in the ways, a size scale to indicate the position of the slide member in the ways, a lever to move the slide member, and a vamp supporting plate mounted to move with the adjustable member and having provision for angular movement.

65 29. The combination with a perforating machine having a cutting block and a perforating die, a block having ways, a slide member adjustable in the ways, means to move the member in the ways, an adjustable connection between the moving means and the slide member to provide an initial setting in accordance with a characteristic of the die, a size scale arranged for co-operation with the moving means to aid in positioning the different sized vamps, and vamp positioning means constructed and arranged to move angularly with respect to the perforating die.

70 30. The combination with a perforating machine having a cutting block and a perforating die, a block having ways, a slide member adjustable in the ways, a link, an adjustable connection between the link and the slide member to provide an initial adjustment in accordance with the style of die, a lever connected to the link, a size scale for co-operation with the lever, and vamp positioning means mounted to move angularly with respect to the perforating die.

75 31. The combination with a perforating machine having a cutting block and a perforating die, a gage plate, a member having ways in which the gage plate slides, a clamp to hold the gage plate in an initially adjusted position on the member in accordance with the style of vamp, and vamp positioning means mounted to move angularly with respect to the perforating die.

80 32. The combination with a perforating machine having a cutting block and a perforating die, a gage plate, a member having ways in which the gage plate slides, a clamp to hold the gage plate in an initially adjusted position on the member in accordance with the style of vamp, a block, means to adjust the member and the gage plate along the block, means to indicate the position of

adjustment in accordance with vamp sizes and a vamp supporting plate adjustable angularly on the gage plate.

33. The combination with a perforating machine having a cutting block and a perforating die, a block having ways, a slide member adjustable in the ways, means to move the member in the ways, an adjustable connection between the moving means and 5 the slide member to provide an initial adjustment in accordance with a characteristic of the die, a gage plate adjustable in ways carried by the slide member, means to clamp the gage plate in initially adjusted position 10 on the slide member in accordance with the style of vamp, and vamp positioning means 15 having provision for angular movement.

34. In a vamp perforating machine, a fixed guide, vamp supporting means 20 mounted to slide on the guide to carry a vamp from a locating to a perforating position, and a cutting block and a perforating die, one of said last-named members being mounted to move with said vamp supporting 25 means.

35. In a vamp perforating machine, the combination of a cutting block, a guide, and a vamp carrier and die movable on the guide to carry a vamp from a vamp positioning 30 to a vamp perforating position.

36. In a vamp perforating machine, the combination of a cutting block, a perforating die for ornamenting a vamp, a stripper on the die to support a portion of a vamp,

and means for supporting the die and 35 stripper for sliding movement to carry a vamp from a vamp positioning to a vamp perforating position.

37. In a vamp perforating machine, the combination of a cutting block, a perforating die for ornamenting a vamp, and a vamp support constructed and arranged to swing on a pivot under perforating pressure. 40

38. In a vamp perforating machine, the combination of a cutting block, a perforating die for ornamenting a vamp, a vamp support, and means to effect an initial adjustment of the vamp support with respect 45 to the perforating die in accordance with a characteristic of the die. 50

39. In a vamp perforating machine, the combination of a cutting block, a perforating die for ornamenting a vamp, a vamp support, and means to effect an initial adjustment of the vamp support with respect 55 to the perforating die in accordance with the style of vamp.

40. In a vamp perforating machine, in combination, a cutting block, a perforating die for ornamenting a vamp, a vamp gage, 60 and lever operated means for effecting successive size adjustments of the gage with respect to the die to ornament the different sizes of vamps progressively.

In testimony whereof I have signed my 65 name to this specification.

CHARLES W. NEWTON.
